US0D1016497S

(12) **United States Design Patent** (10) **Patent No.:** **US D1,016,497 S**
(45) **Date of Patent:** **** Mar. 5, 2024**

(54) **EXPANDED SHEET**

(71) Applicant: **3M INNOVATIVE PROPERTIES COMPANY**, St. Paul, MN (US)

(72) Inventor: **Thomas R. Corrigan**, St. Paul, MN (US)

(73) Assignee: **3M INNOVATIVE PROPERTIES COMPANY**, St. Paul, MN (US)

(**) Term: **15 Years**

(21) Appl. No.: **29/744,506**

(22) Filed: **Jul. 29, 2020**

(51) LOC (14) Cl. **05-06**

(52) U.S. Cl.

USPC **D5/99**

(58) **Field of Classification Search**

USPC D5/1, 4, 19, 23, 30, 40, 43, 47, 48, 54,

(57) **CLAIM**

The ornamental design for an expanded sheet, as shown and described.

DESCRIPTION

FIG. 1 is a perspective view of an expanded sheet showing the new design;

FIG. 2 is a front view thereof;

FIG. 3 is a back view thereof;

FIG. 4 is left side view thereof;

FIG. 5 is a right side view thereof;

FIG. 6 is top view thereof; and,

FIG. 7 is a bottom view thereof.

1 Claim, 5 Drawing Sheets
